CLAIM

The ornamental design for a decorative head cover, as shown and described.

DESCRIPTION

FIG. 1 is a front elevation view of a decorative head cover; FIG. 2 is a rear elevation view thereof;

FIG. 3 is a left side elevation view thereof, wherein the left side elevation view and the right side elevation view are identical; and,

FIG. 4 is a top plan view thereof.

The broken lines in the drawings represent environmental structure that form no part of the claimed design.
